UNITED STATES PATENT OFFICE.

WENZEL ERNST MIKSCH, OF VIENNA, AUSTRIA-HUNGARY.

ROOFING-TILE.

No. 801,736.

Specification of Letters Patent.

Patented Oct. 10, 1905.

Application filed February 28, 1905. Serial No. 247,764.

To all whom it may concern:

Be it known that I, WENZEL ERNST MIKSCH, a subject of the Emperor of Austria-Hungary, and a resident of Vienna, in Austria-Hungary, have invented a certain new and useful Roofing-Tile, of which the following is a specification.

This invention relates to tiles formed either by molding each one separately or by cutting lengths from a continuous strip of clay, and it especially relates to grooved roofing-tiles having ribs or lips on their under side, which lips rest on the roof-laths, and according to this invention these ribs engage the laths by means of shoulders and are provided above the said shoulders with grooves in the case of continuously-formed tiles and with recesses in the case of separately-molded tiles, which recesses extend inward to such an extent that at the joint of the tiles the head of a double-headed hook, serving to hold two adjacent tiles to be secured to the roof-lath in position, can be introduced flat between the ribs and then turned transversely, whereby the tiles are secured. The said double-headed hook is then secured to the roof-lath. In this way the roof is covered in a perfectly secure and weatherproof manner, as the double hooks are completely inclosed and the tiles are held by the hook directly over the point at which the ribs engage the laths. This, in combination with the grooving, prevents rain or snow from driving under and gales from lifting off the tiles.

A tile according to this invention is illustrated, by way of example, in the accompanying drawings, in which—

Figure 1 is a plan of a molded grooved tile, and Fig. 2 an inverted plan of same. Fig. 3 is a longitudinal section of a continuous tile-covering with a portion of a ridge-tile. Fig. 3^a shows the covering and the fixing of molded grooved tile on a larger scale. Fig. 4 is a plan, and Fig. 5 an inverted plan, of a continuous tile. Fig. 6 shows the covering and fixing of continuously-formed grooved tiles, and Fig. 6^a the covering and fixing of the same on a larger scale. Fig. 7 is an end view of continuously-formed grooved tiles placed on the top of each other with their support and fixing. Fig. 8 is a plan of a ridge-tile suitable

for securing by a hook, and Fig. 9 is an inverted plan of the same. Fig. 10 is an end view of a ridge-tile. Fig. 11 shows the double hook used for fixing. 55

The grooved tile is provided with the usual lateral grooves *a* and lower lateral carrying ribs or lips *b*, which rest with shoulders *c* on the roofing-laths, whereby the roofing-tile is maintained in an oblique position, while in 60 molded grooved tiles, Figs. 1 and 2, the bottom edge *d* of the tile, projecting beyond the carrying-ribs *b*, overlaps the beaded edge *e* of the next lower molded grooved tile, and thus not only prevents the latter from sliding down 65 the roof, but also prevents rain and snow from driving in. In the continuous-grooved tiles this is effected by a larger amount of overlapping. Lateral as well as downward movement of grooved tiles is prevented, according 70 to this invention, by two tiles, whether molded or continuous, arranged next to each other, being held fast at their opposite support ribs or lips *b* by means of a double hook *f*, which in the case of molded grooved tiles engages 75 the recess *g* by means of its double head, and in the case of continuously-formed tiles the said double head engages the groove *g'*, the said hook being secured to the roofing-lath in any suitable manner—for example, by means 80 of a wire nail passing through its eye, as shown in Figs. 3, 3^a, 6, and 6^a of the drawings.

The covering of a roof with the above-described grooved tiles is effected in the usual manner. The double-headed hooks *f* are introduced from the bottom of the roof, with their double heads parallel to the tile, between the two recesses *g* or grooves *g'* of each two adjoining grooved tiles. Then by turning the hook through an angle of ninety degrees it is 85 caused to engage with the said recesses or grooves, whereupon the hook is secured to the roofing-lath, as above described. The covering of the roof is thus effected in a very simple manner, and just as simple is any removal or exchange of single tiles, which can be easily effected by removing the double-headed hook, this being possible without loosening the adjoining tiles. 95

What I claim as my invention, and desire to 100 secure by Letters Patent, is—

A roofing-tile comprising a body, ribs pro-

jecting from the under side of the tile-body, adjacent to its lateral edges and grooved longitudinally, adapted to be engaged by securing means and shoulders on the ribs arranged 5 to bear upon the roof-laths, substantially as set forth.

In testimony whereof I have signed my name

to this specification in the presence of two subscribing witnesses.

WENZEL ERNST MIKSCH.
